THREAD GUIDE

Earnest H. Scott, Burlington, N. C.

Application March 12, 1951, Serial No. 215,090

2 Claims. (Cl. 66—135)

1

This invention relates to circular knitting machines and more particularly to an improved threaded guide in combination with yarn bobbins and yarn feeding mechanisms of such machines.

While the invention is applicable to other types of knitting machines, it is particularly suited to a knitting machine wherein a plurality of thread or yarn supply bobbins are mounted about the outer peripheral portion of a rotatable stand. In machines of this type, the thread or yarn bobbin is of generally elongated cylindrical shape and a large number (usually eighteen, more or less) of bobbins, are vertically mounted on the rotatable stand in rather close proximity to each other. When the machine is in operation, the stand, and hence the bobbins mounted thereon, rotates at high speed. The thread or yarn on each of the bobbins is continuously being fed to the knitting needles through suitable tensioning devices, yarn feed assemblies, etc. The tensioning devices are usually mounted above and in vertical alignment with the bobbin stand and rotate therewith. It has been a long and serious problem in the above type of knitting machine to prevent the yarn of one bobbin from becoming entangled and twisted with the yarn of an adjacent bobbin. When the bobbin stand and tensioning devices are rotated at high speeds, centrifugal force causes the yarn to bow outwardly between the bobbins and the tensioning devices. If the bowing of the yarns is great enough, the bowed yarn having one bobbin to its tensioning device will contact an adjacent bobbin and/or the yarn being drawn from such adjacent bobbin. When this occurs, the whipping and bowing of the yarns are frequently sufficient to cause entanglement of adjacent yarns to such extent that the yarns will break at some point between the bobbins and the tensioning devices. Of course, when breakage of the yarn occurs, it is necessary to shut the machine down, untangle the yarns and thereafter re-threaded the same.

In commercial mill practices, it is not uncommon to have to shut down a machine many times a day to untangle yarns which have become twisted and entangled with each other between the bobbins and the tensioning devices. Time and labor to untwist and re-threaded yarns on a machine of this type is considerable, and loss of production of the machine, together with labor costs, make yarn twisting and breaking a problem of serious financial proportions.

Accordingly, the principal object of the present invention is to prevent entanglement of yarns between bobbins and tensioning devices, particularly in a circular knitting machine.

Another important object of the invention is to prevent entanglement of yarns between the

5 bobbins and tensioning devices of a circular knitting machine in an inexpensive, efficient manner, wherein the initial cost and installation is negligible, wherein no additional maintenance of the machine is required, and wherein the means for preventing the yarn entanglement does not create additional yarn threading impediments.

10 Further objects and advantages of the invention will be apparent with reference to the following specification and drawings in which:

15 Fig. 1 is a view partly in elevation and partly in section of a portion of the head of a circular knitting machine equipped with the thread guide of this invention; and

20 Fig. 2 is an underside plan view of the thread guide of this invention.

25 The invention is shown embodied in the well known Scott and Williams seamless hosiery knitting machine, such as for instance that shown and described in the patent to Robert W. Scott, No. 1,152,580, issued September 7, 1915, and the patents to A. E. Page, Nos. 1,853,020 and 1,906,204, issued April 5, 1932, and April 25, 1933, respectively.

30 Inasmuch as the Scott and Williams circular knitting machine is well known and is completely described in the patents mentioned above, only a description of that portion of the machine necessary for an understanding of the present invention will be made.

35 The circular knitting machine of the type under consideration customarily includes a circular rotatable yarn bobbin stand 10 adapted to be rotated at high speeds by the ring gear 11 which is fixed to a bobbin stand sleeve 12, the latter being rotatably journaled at 13 on the framework 14 of the machine. A plurality of substantially cylindrical yarn bobbins, only two of which are shown at 15 and 16, are pivotally carried at 23 and 24 about the entire periphery of the bobbin stand 10, the bobbins being mounted in spaced relation and in rather close proximity to each other. A yarn take-up bracket 17 is carried above the bobbin stand 10 by the bobbin stand shaft 18 and fixed thereto to revolve with the yarn bobbin stand 10, inasmuch as the bobbin stand shaft 18 is also fixed to the bobbin stand sleeve 12. A plurality of yarn take-ups of the pivoted arm type such as that shown at 18' are provided on the upper surface of the take-up bracket 17 to maintain tension on the yarn fed from the bobbins through the usual tension disk such as shown at 19.

40 45 50 55 Secured to the underside of the take-up bracket 17 by a plurality of angle brackets 20 and 21 in a manner to extend beneath the bracket 17 is a circular thread guide ring 22. The angle brackets

20 and 21 have suitable threaded bolts *f* or attachment to the bracket 17. The vertical portions of the angle brackets are of sufficient length to permit the ring 22 to be positioned just above the top portions of the yarn bobbins 15 and 16, as shown. The thread guide ring 22 is more clearly shown in Fig. 2 of the drawing and is comprised of a ring of suitable material such as metal, although the ring may, of course, be made of other material such as plastic or the like. The thread guide ring 22 may have a median diameter equal to the diameter of rotatable yarn bobbin stand at the pivot points of the bobbins such as shown at 23 and 24 (see Fig. 1). The ring 22 is provided with a plurality of openings 23, one for each bobbin, and preferably located to be positioned just above and in alignment with each bobbin when installed on the machine. The plan view of Fig. 2 of the drawing is a view of the underside of the ring 22 and shows how the edges of the openings 23, preferably circular, are bevelled inward of the opening as indicated at 24. The bevelling of the openings prevents wear or damage to the yarn as the same is drawn therethrough.

A more important function of the bevel portion 24 of the openings 23 is to permit the application of the bobbins to the machine. As will be noted in Fig. 1 of the drawings, the ring 22 is positioned just above the end of the bobbins. When it is desired to remove a bobbin, the bobbin is raised within the opening 23 sufficient to permit clearance of the bobbin at its bottom portion with relation to the bobbin spindle which is shown by the dotted lines on Fig. 1. The bobbin to be removed may then be tilted outward as permitted by the bevel portion 24 and removed from the machine. To apply a new bobbin, the above procedure is simply reversed and it will be noted that it is not necessary to remove the ring 22 when applying or removing bobbins.

When a machine not utilizing this invention is in operation, the yarn bobbin stand (and bobbins mounted thereon) is rotated at a high speed, and the individual yarns will have a tendency to bow outwardly as they leave the bobbins. When the yarns are being drawn from a point adjacent the top of the bobbins, the distance from such point to the tensioning devices is relatively short and the centrifugal force caused by the rotation is insufficient to create large bows in the yarn and hence they do not spread out sufficiently to become entangled with each other. However, when the yarn is being pulled from the bobbins at lower points, particularly at points near or at the bottom of the bobbins, the distance from such points to the tensioning devices becomes materially greater, thus resulting in more yarn susceptible to centrifugal force and hence resulting in larger bows. It is at such times during the operation of the machine that one yarn may bow sufficiently to become entangled with an adjacent yarn, particularly if the adjacent yarn is being removed from the bobbin at or near the top thereof, and hence has only a small bow therein.

When utilizing applicant's invention, the yarn bobbin stand 10 (and hence the bobbins mounted thereon) is rotated at a high speed in the usual manner. As the take-up bracket 17 is being rotated at the same speed as the stand 10 and as the guide ring 22 is bolted in fixed position on the bracket 17, then it follows that the stand 10, bracket 17 and ring 22 are simultaneously rotated at the same speeds. The yarns are

threaded through their respective openings 23 formed in the ring 22 and thence to their respective take-up 18'. By positioning the ring closely adjacent to the top portions of the bobbins, it is then substantially midway between the lower portions of the bobbins and the take-ups 18'. Hence, when yarn is being removed from the bobbins at or near the bottom thereof, the ring 22 will prevent the free yarn from bowing outwardly as the axis of the yarn openings in the ring is in alignment with its respective bobbin. Accordingly, the yarns can never bow outwardly to any greater extent than they would normally bow when they are being removed from their bobbins at points adjacent to the top of the bobbins. As previously mentioned, the extent of the bowing between the top portion of the bobbins and the take-ups is insufficient to cause entanglement of the yarns.

I claim:

1. In a circular knitting machine, a rotatable yarn bobbin stand, a plurality of substantially cylindrical yarn bobbins mounted vertically and in spaced relation on said stand in substantially circular formation, a yarn take-up bracket positioned above said stand, a thread guide ring, means for mounting said ring on said bracket so as to position the same beneath said bracket and in close proximity to the upper portions of said bobbins, said ring having a plurality of circular openings therein, said openings being of a size to permit at least a portion of the bobbin to be inserted therein when it is desired to remove the bobbin from the machine, each opening being in substantially vertical alignment with each of said bobbins, so that the yarn being drawn from each bobbin will pass through its respective opening in said ring to said take-up bracket.

2. In a circular knitting machine, a rotatable yarn bobbin stand, a plurality of substantially cylindrical yarn bobbins mounted vertically and in spaced relation on said stand in substantially circular formation, a yarn take-up bracket positioned above said stand, a thread guide ring, means for mounting said ring on said bracket so as to position the same beneath said bracket and in close proximity to the upper portions of said bobbins, said ring having a plurality of circular openings therein, said openings being of a size to permit at least a portion of the bobbin to be inserted therein when it is desired to remove the bobbin from the machine, each opening being in substantially vertical alignment with each of said bobbins, so that the yarn being drawn from each bobbin will pass through its respective opening in said ring to said take-up bracket, the underside of each of said openings being bevelled inward of the opening.
